UNITED STATES PATENT OFFICE.

JOSEPH BOYER, OF DETROIT, MICHIGAN, ASSIGNOR TO CHICAGO PNEUMATIC TOOL COMPANY, OF CHICAGO, ILLINOIS, A CORPORATION OF NEW JERSEY.

PNEUMATIC HAMMER.

No. 866,573.

Specification of Letters Patent.

Patented Sept. 17, 1907.

Original application filed September 26, 1899, Serial No. 731,720. Divided and this application filed August 10, 1905.
Serial No. 273,616.

To all whom it may concern

Be it known that I, JOSEPH BOYER, a citizen of the United States, formerly residing at St. Louis, Missouri, but now residing at Detroit, Wayne county, Michigan, have invented certain new and useful Improvements in Pneumatic Hammers, of which the following is a specification.

My invention relates to pneumatic hammers, and more particularly means for holding the working tool, 10 such as a chisel or rivet set, to the forward or outer end of the cylinder or barrel of the hammer.

The object of my invention is to provide a simple and efficient device or means of this character and at the same time make provision for a relative limited movement of one of such parts with respect to the other.

According to the within described embodiment of my invention, such device consists of a clip of spring metal such as thin sheet steel, arranged to engage or grip one of said parts (in the present instance the cylinder) 20 without relative longitudinal movement thereon, but arranged to loosely engage the other part (in the present instance the working tool or rivet set) in such manner as that the latter will have a relative movement longitudinally. The clip is so constructed as to readily permit the removal of the working tool or the substitution of another one whenever desired, but such clip when in place is arranged to securely connect the working tool to the cylinder and also permit the limited longitudinal movement referred to.

30 In the accompanying drawing, Figure 1 is a side elevation of a pneumatic hammer with the forward end thereof in section to illustrate my spring clip and its cooperation with the forward end of the cylinder and the working tool; and Fig. 2 a perspective view of the clip.

35 The particular hammer herein illustrated is of the type commonly known as the Boyer long stroke hammer, but it is obvious that my invention is not to be limited to any particular type or make of hammer, but that it may be applied to hammers of different construction and of different make, without departing from the spirit and scope of my invention and claims.

40 Referring to the drawing, the hammer therein illustrated comprises a cylinder or barrel A having secured to its rearward end the usual grasping handle B. The 45 particular type of hammer herein shown happens to have a nose-piece E secured to the front of the cylinder, but so far as my invention is concerned, such nose-piece forms in effect a part of the cylinder itself and will so be considered in the subsequent description and in the 50 claims following. As usual, the cylinder is provided at its front end with an opening, which is arranged to receive the shank of a working tool which, in the present illustration, is a rivet set F.

For the purpose of detachably connecting the work-

ing tool or rivet set to the cylinder and hold it against displacement, I employ the clip G which is shown in section in Fig. 1, and in perspective in Fig. 2. This clip may be made of suitable spring metal, such as thin sheet steel rolled in circular form but open or split at one side so as to partially surround the cylinder and 55 working tool. The clip is provided at its opposite ends and at opposite sides with pairs of inturned flanges g g¹ which are arranged to engage circumferential grooves on the cylinder and working tool respectively. In the present instance and by preference, the front end of the 60 cylinder is provided with an annular rearwardly facing shoulder formed by a circumferential groove G¹ to receive one pair of the flanges, say the pair g, and of a width so as to be stationarily held to the cylinder, as 65 against longitudinal movement, one with respect to the 70 other. In order to permit the working tool to have a longitudinal movement to a limited extent with respect to the cylinder, I provide the working tool with a corresponding annular forwardly facing shoulder formed by a circumferential groove G² which is relatively 75 wider and adapted to receive the other pair of flanges g¹, with the result that the working tool is permitted to move longitudinally with respect to the cylinder to a limited extent, that is the working tool is permitted to move outwardly until its flange or shoulder f contacts 80 the inturned flanges g¹, the degree of such movement being determined by the width of the circumferential groove G². When the working tool or rivet set is to be removed from or inserted into the hammer the ends of the clip G are sprung apart in suitable manner, as by 85 means of a pair of pliers, whereupon the shoulder f upon the rivet set may readily pass the flanges upon the clip, as such set is withdrawn or inserted.

By the use of my invention, the working tool or rivet set is not only properly held at the front of the cylinder 90 in a detachable manner by the employment of a simple and efficient device, but is permitted to have a longitudinal movement or play with respect to the cylinder, with the result that the clip is relieved of the force and jar of the blow delivered by the hammering piston to 95 the rivet set. Moreover, this limited movement or play of the rivet set permits of the operation of the automatic throttle valve forming a part of the subject matter of the original application, of which the present is a division, which automatic valve is located at the rearward end of the cylinder and arranged to be automatically 100 opened by the act of pressing the tool or rivet set to the work.

Although I contemplate using my invention wherever applicable, the same has particular application to 105 what are generally known as riveting hammers, in which it is desirable, if not required, that the rivet set shall be held in detachable manner to the cylinder or

body of the tool or hammer proper so as to prevent the rivet set from dropping out or from being shot out, the shank of such rivet set in this type of hammer, as illustrated in the drawing, being such as to close the bore 5 or opening in the front end of the cylinder.

I claim:

1. In a pneumatic hammer, the combination, with the cylinder thereof and with a removable working tool insertible in the front end of such cylinder, of a spring clip carried by one of said parts, partially surrounding said parts and having a shoulder or detent adapted to co-operate with a shoulder or detent on the other of said parts and hold them together and permitting a limited longitudinal movement of one with respect to the other: 10 substantially as described.
2. In a pneumatic hammer, the combination, with the cylinder thereof and with a removable working tool insertible in the front end of such cylinder, said parts having grooves at their adjacent ends, of a spring clip having 20 means arranged to engage said grooves, one of said grooves being relatively wider to permit limited reciprocation of one of said parts with respect to the other; substantially as described.
3. In a pneumatic hammer, the combination, with the cylinder thereof and with a removable working tool insertible in the front end of such cylinder, of a spring clip co-operating with said parts to hold them together and provided at its ends with inturned flanges, one of said parts having a circumferential groove of a width to receive and stationarily hold the flange at one end of the clip, and the other of said parts having a relatively wide circumferential groove to receive the flange at the other end of the clip, thereby permitting limited reciprocation of the tool relatively to the cylinder; substantially as described. 30
4. In a pneumatic hammer, the combination, with the cylinder thereof and with a removable working tool insertible in the front end of such cylinder, of a spring clip co-operating with said parts to hold them together and provided at its ends with inturned flanges, the cylinder having a groove of a width to receive and stationarily hold the flange at the rear end of the clip and the working tool having a wide groove to receive the flange at the front end of the clip and permit limited reciprocation 40 of the tool relatively to the cylinder; substantially as described.
5. In a pneumatic hammer, the combination, with the cylinder thereof and with a removable working tool insertible in the front end of such cylinder, of a spring clip co-operating with said parts to detachably connect the working tool with the cylinder, the clip being open on one side and provided at each end with a pair of opposite and inturned flanges, the cylinder having a groove to receive the pair of flanges at one end of the clip and the working tool having a wide groove to receive the pair of flanges at the other end of the clip and to permit a limited movement or play of the working tool; substantially as described. 50
6. In a pneumatic hammer, the combination with the

cylinder or body of the tool provided near its front end .60 with a rearwardly facing annular shoulder, and the removable working tool having its shank inserted in the front end of said body, and provided with a forwardly facing annular shoulder, of a spring clip partially surrounding said parts and provided at its front and rear 65 ends with inturned flanges engaging said annular shoulders to prevent displacement of the working tool, substantially as described.

7. In a pneumatic hammer, the combination with the cylinder or body of the tool provided with a circumferential groove near its front end, and the removable working tool having a shank inserted in the front end of said cylinder, and provided with a forwardly facing annular shoulder, of a spring clip surrounding said parts and provided at its front and rear ends with inturned flanges engaging 70 said groove and annular shoulder, respectively, to prevent displacement of the working tool; substantially as described.

8. In a pneumatic hammer, the combination with the cylinder or body of the tool provided with a circumferential groove near its front end, and the removable working tool having the shank inserted in the front end of said body and provided also with a circumferential groove, of a spring clip partially surrounding said parts and provided at its front and rear ends with inturned flanges 80 engaging said groove; substantially as described.

9. In a pneumatic hammer, the combination with the cylinder or body of the tool provided near its front end with a circumferential groove, and the removable working tool having the shank inserted in the front end of said body and provided also with a wide circumferential groove adjacent the front end of said body, of a spring clip partially surrounding said parts and provided at its front and rear ends with inturned flanges engaging said groove, the relatively wide groove of the working tool permitting 90 limited reciprocation of the latter relatively to the spring clip and body of the tool; substantially as described.

10. In a pneumatic hammer, the combination with the cylinder or body of the tool having its front end E provided with a circumferential groove, and the removable working tool having the shank F inserted in the central bore in the said front end of the body of the tool, and provided also with the wide circumferential groove adjacent the front end of said body, of the spring clip G partially surrounding said parts and provided at its front 100 and rear ends with the inturned flanges engaging said groove; substantially as described.

11. In a pneumatic hammer, the combination, with the cylinder or body of the tool formed at its front end to receive the shank of the working tool and provided with 110 the circumferential groove G¹, of the working tool provided with said shank and the circumferential groove G², and the clip G provided at its opposite ends with the inturned flanges engaging the grooves G¹ and G², respectively; substantially as described.

JOSEPH BOYER.
